WALL PLAQUE

Franklin McKeever Wills, Chicago, Ill., assignor to Arabesque, Inc., Chicago, Ill., a corporation of Illinois

Application September 16, 1957, Serial No. 47,739

Term of patent 14 years

(Cl. D29—23)

Fig. 1 is a front elevational view of a wall plaque, showing my new design;

Fig. 2 is a side elevational view looking from the left of Fig. 1;

Fig. 3 is a top plan view;

Fig. 4 is a side elevational view looking from the right of Fig. 1; and

Fig. 5 is a bottom plan view thereof.

I claim:

The ornamental design for a wall plaque, substantially as shown.
